ATTORNEY

UNITED STATES PATENT OFFICE

WILLIAM G. KENDALL, OF NEWARK, NEW JERSEY

VANITY CASE

Application filed November 12, 1929. Serial No. 406,646.

This invention relates to vanity cases, and particularly to an improved construction wherein a holding and ejecting mechanism is either formed as part of the case or part of attachments intimately associated with the case, the object being to accomplish these results in a simple and yet efficient manner.

Another object of the invention is to provide an improved construction wherein either 10 part of the body of a vanity case or a member connected therewith acts as an ejecting means to eject the compact plate whenever necessary or desired.

A further object of the invention is to provide a vanity case in which a diaphragm or other vibrating member is used to eject a compact plate.

A further object, more specifically, is to provide a vanity case in which holding means 20 are arranged around the edge for holding a compact plate resiliently in the vanity case and with projections extending from the bottom which act to eject the compact plate when the bottom is flexed to a certain extent.

25 In the accompanying drawing,—

Figure 1 is a plan view of a vanity case constructed according to the present invention, the lid or cover being shown swung to an open position;

30 Figure 2 is a sectional view through Figure 1 on the line 2—2;

Figure 3 is a fragmentary plan view of the body of a vanity case showing a modified arrangement of ejecting means;

35 Figure 4 is a view similar to Figure 3 but showing a further modified form of ejecting means;

Figure 5 is a sectional view similar to Figure 2 but showing a modified form of ejecting means;

40 Figure 6 is a view similar to Figure 5 but showing the parts moved to an ejecting position;

45 Figure 7 is a sectional view showing a modified form of the structure shown in Figure 5;

Figure 8 is a sectional view through the body of the vanity case showing a further modified form of the invention to that illustrated in Figure 5;

50 Figure 9 is a fragmentary top plan view of

a vanity case having an irregular contour provided with compact plate holding and ejecting means embodying the invention;

Figure 10 is a sectional view through Figure 9 on the line 10—10;

55 Figure 11 is a view similar to Figure 10 but showing a modified form of the invention;

Figure 12 is a further modified form of the invention wherein the ejecting nib is made 60 separate and secured in position;

Figure 13 is a further or additional modified form of the invention wherein the bottom of the vanity case is burred to produce an inwardly-extending nib or projection.

65 Referring to the accompanying drawings by numerals, 1 indicates the body of a vanity case, and 2 the cover or lid connected to body 1 by any suitable means, as for instance, hinge 3. Body 1 may be of any desired shape, 70 but that shown in Figure 1 is round, and from the sides there are pressed a number of nibs 4 which, with the side walls of the body, are more or less resilient, and consequently, act to resiliently hold the compact plate 5 in place, as shown in Figure 2. When the powder in this case has been used, and it is desired to supply a new compact the plate must be removed before the new compact and new compact plate can be inserted.

75 In many instances it is desired to remove a filled compact plate and various ejecting means have been provided heretofore to accomplish this result. Some of these ejecting means, while functioning properly as ejecting means, had a tendency to crack or break the compact. Where compacts were being substituted in the stores this breaking of the compact was very objectionable, as it immediately became unsalable.

80 In the present instance an ejecting structure has been provided which will eject an empty compact plate or one which is filled. Where the filled compact plate is ejected the operation is such that there is no cracking of the powder cake or no scratching thereof, as the ejecting member acts on the bottom of the plate.

85 In this way the compacts may be readily ejected and others substituted in stores to suit the differ-

ent customers without danger of injuring any of the compacts.

As shown particularly in Figure 2 of the accompanying drawing, the ejector consists of the nib or protrusion 6 preferably formed integral with the flexible or resilient bottom 7. If desired, the projection or nib 6 may be made separately and secured in place, and when once arranged in place the entire structure will function as shown in Figure 2. The bottom 7 acts as the bottom of body 1 and may be an ordinary metallic body as now on the market. Most, if not all, of the metallic vanity cases have a very thin bottom and will readily flex, so that by the provision of a nib or other projection 6 they may act as a diaphragm and permit the nib to eject the compact plate when pressure is brought to bear on the bottom. Under some circumstances the nib 6 may not be necessary, but in such cases the bottom should be very flexible so as to move a sufficient distance to move the plate 5 past the holding nibs 4 or other holding means.

In Figure 3 the same structure is shown as illustrated in Figures 1 and 2, except that there is provided a group of nibs or projections 6'. The function of this structure is identical with the function of the single nib 6 shown in Figure 2, but permits contact over spaced points, so that if there should be any irregularity in the plate 5, one of the nibs 6' would contact properly and thereby transmit movement from the bottom 7 to the plate 5.

In Figure 4 a similar structure is shown to that illustrated in Figures 2 and 3, except that the single nib 6'' is formed as a star, whereby the same is ornamental, as well as useful. The action is the same, but by this structure the nib can be pressed upwardly to a greater distance, if desired, without cracking or injuring the bottom 7.

In Figures 5 and 6 a modified form of the invention is shown, wherein the body 1 is formed with a bottom 8 having a bent-up annular section 9, whereby a groove 10 is provided. This arrangement causes the main part or center of the bottom to flex to a large extent, and this diaphragm or flexing action is sufficient, by reason of the bent-up part 9, to eject the compact 11 with its plate 12. This plate is held in position by the usual nibs 4 which resiliently pinch the plate, but which are not sufficiently strong to prevent an upward pressure by the fingers or thumb of a person on bottom 8 from moving the plate 12. As shown in Figure 6, the bottom 8 has been deformed or bowed upwardly and the plate 12 moved out of engagement with the nibs 4, whereupon the plate and its powder cake may be readily discharged by inverting body 1. Usually the parts are so formed that bottom 8 will automatically re-

turn to the position shown in Figure 5 when released by the thumb or fingers.

Figure 7 shows another form of the invention, wherein the bottom 13 is similar to bottom 8 but provided with two annular bent-up portions 14 and 15, whereby a double flexing action is secured and the center of bottom 13 permitted to move up a greater distance, if desired. It will be noted that the compact plate 16 in this form of the invention is merely a dished plate held resiliently in place by the nibs 4. Upon pressing upwardly on the center of bottom 13 plate 16 will be ejected or forced past the nibs 4, and consequently, will be loose, so that by inverting the body 17 the compact plate will fall out. In case the compact 18 is still on the plate, this ejecting action will not injure the powder cake so that it may be again inserted or may be placed in another case.

Figure 8 shows a further modified form of the invention which is identical with that shown in Figure 7, except that three bent-up portions 19, 20 and 21 are provided, so that a greater upward movement of the center of the bottom 22 may be made.

In Figures 9 and 10 a further form of the invention is shown wherein the body 23 is irregular in outline, and in order to accommodate the ordinary, round compact plate 24, a holding ring 25 is used. This is shown as an L-shaped ring, though it could be made of some other shape. This ring is provided with nibs 4' similar to nibs 4. The bottom 26 of the body 23 is flexible and is provided with a pressed-up nib or projection 27, said nib or projection being centrally of the bottom, though it could be at one side, if desired. The bottom 29 acts somewhat on the order of a diaphragm and is naturally a very thin metal, so that it can flex a short distance, as for instance, a sixteenth or an eighth of an inch. This movement will be sufficient to force the compact plate 24 out of engagement with the nibs 4', and consequently, the plate is ejected.

In Figure 11 a further slightly modified structure is shown, wherein the body 28 is of a shape which answers certain demands of the market and is well-known except for the annular pressed-up portion 29 and the pressed-up nib 30. The holding ring 31 may be of a kind now on the market, as for instance, similar to one of the rings in one of my prior patents. This ring is provided with a pressed-out nib 4'' which functions similar to nib 4 or 4' and normally holds the plate 32 in place. The annular pressed-up portion 29 causes the bottom 33 to be more flexible or permits a greater flex thereof, so that when pressed the nib 30 will be moved sufficiently far to disengage plate 32 from nibs 4''. In this form of the invention and all the other forms the bottom is formed or provided with means which

may be moved inwardly and thereby push the compact plate from its resilient fastening members 4.

In Figure 12 a modified form of the invention is shown wherein the projection or nib 33 is separate from the bottom 34 but secured thereto in any desired manner. This nib may be metal and soldered or otherwise secured in place, or may be merely a comparatively large lump of solder which automatically adheres to the bottom 34.

In Figure 13 an additional form of projection 35 is presented. This projection is formed by burring the interior surface of the bottom 36 so that, although the burr 35 is integral with the bottom, it is not pressed inwardly, as shown in Figures 1 and 2, but projects inwardly a sufficient distance to function in the same manner as the nib 6.

20 What I claim is:—

1. A vanity case, including a body having a flexible bottom, means carried by the body for normally holding a compact plate in the body, and means carried by the bottom acting 25 to eject said plate when the last-mentioned means has been moved inwardly.

2. A vanity case, including a metal body having a flexible bottom provided with an inwardly-extending projection acting with 30 the flexible bottom as means for ejecting a compact plate.

3. A vanity case, including a body having a compact plate holding means and a flexible bottom formed with an integral inwardly-extending projection of a length to substantially touch said compact plate, whereby when 35 said bottom is flexed inwardly, said projection will force said compact plate out of engagement with said holding means and thereby eject the same.

40 4. A vanity case, including a body having a flexible bottom and means acting to hold a compact plate, said bottom being capable of being flexed to such an extent as to eject said compact plate.

45 5. A vanity case, including a body having a flexible bottom provided with an inwardly-extending projection positioned centrally of the bottom, and means carried by the body for normally holding a compact in the body, said flexible bottom coacting with 50 said projection to force the compact to a disengaged position when the bottom has been flexed inwardly.

55 6. A vanity case, including a body having flexible side walls and a flexible bottom, means carried by the side walls to resiliently hold a compact plate in the body, and means carried by the bottom interiorly thereof for 60 providing an ejecting connection between the bottom and the compact plate, whereby when the bottom is deflected inwardly, said means will force the compact plate out of engagement with the holding means.

65 7. A vanity case, including a body having

a flexible bottom formed with a centrally disposed inwardly-extending projection, said body being also provided with compact plate holding means.

8. A vanity case, including a body having a plurality of holding means for holding a compact plate in the body, and a bottom having a portion deflected inwardly substantially central thereof. 70

9. A vanity case, including a body, means for resiliently holding a compact plate in the body, a flexible bottom for said body, and a connecting member carried by said bottom positioned to be normally in contact with the bottom of said compact plate, whereby when said bottom is flexed inwardly said connecting member will push the compact plate out of engagement with said resilient holding means. 75

10. A vanity case, including a body having means for resiliently holding a compact plate in the body, and a flexible bottom having a nib pressed inwardly from the point in contact with the said compact plate whereby when said bottom is pressed inwardly said compact plate will be moved out of engagement with said holding means. 80
